UNITED STATES PATENT OFFICE.

WALTER THORSTEINSON, OF WINNIPEG, MANITOBA, CANADA.

SWITCH-POINT-CONTROLLING DEVICE.

1,089,685.

Specification of Letters Patent. Patented Mar. 10, 1914.

Application filed October 14, 1912. Serial No. 725,585.

To all whom it may concern:

Be it known that I, WALTER THORSTEINSON, of the city of Winnipeg, in the Province of Manitoba, Canada, have invented 5 certain new and useful Improvements in Switch-Point-Controlling Devices, of which the following is the specification.

The invention relates to a device for throwing switch points of railways, particularly those of street car lines and the object of the invention is to provide an inexpensive, durable easily applied device which will effectively throw a switch point when operated the device being controlled from 15 the car by the motorman.

It consists essentially in a pair of hooked bars located beneath the car floor slightly in advance of the car wheel flanges, such bars being supported and manipulated so 20 that one or other can be swung downwardly to catch the switch point and then be moved in a direction across the track to pull the switch point to cause the car to take the switch, the parts being arranged and constructed as hereinafter more particularly 25 described.

Figure 1 represents a front view of a car with my device applied parts being broken away to expose construction. Fig. 2 represents a plan view of the car and a portion of the track showing the switch point, part of the car being broken away to expose construction. Fig. 3 is a horizontal sectional view through the apparatus to an enlarged 35 scale, the section being taken in the plane denoted by the line X—X' Fig. 1 the box and parts contained thereby being shown in plan view. Fig. 4 is an enlarged detailed side elevation of the upper end of one of 40 the foot trips.

In the drawing like characters of reference indicate corresponding parts in each figure.

1 represents a street car of ordinary construction of which 2 is the vestibule, 3 the front buffer, 4 the floor, 5 the controller, and 6 the front trucks provided with the usual flanged wheels 7 and 8 which ride on the tracks 9 and 10.

50 11 represents a switch point pivoted on an upright pin 12 as is customary and designed to turn the car on to the side tracks 13 and 14.

55 15 is a horizontally disposed open ended box carried by two brackets 16 and 17 passing upwardly to the car floor where they

are permanently fastened. The box receives slidably the inner ends of two opposing similar rack bars 18 and 19 receiving between them a pinion 20 carried by an upwardly directed shaft 21 having the lower end suitably mounted in the box and the body portion thereof suitably mounted in the car floor. The upper end of the shaft enters the vestibule and is fitted with a hand lever 22 positioned conveniently to the motorman. 23 and 24 are two oppositely directed bars having their inner ends pivotally secured by pins 25 to the outer ends of the rack bars. The outer ends of the bars 70 are hooked at 26 and 27 which hooks are designed to catch and pull over the switch points of the car tracks when operated as shortly described. The bars 24 and 25 are supported by upright rods 28 and 29 pivotally secured by pins 30 to the rods and having the body portion thereof slidably mounted in brackets 31 secured to the car floor. The rods protrude through the car floor and have their upper ends enlarged to 80 form foot pedals or trips 32. Spiral springs 33 encircle the rods and have their lower ends resting on the brackets 31 and their upper ends engaging with cross pins 34 carried by the respective rods. These springs 85 tend normally to hold the rods carrying the hooked bars in their upper positions. The rods are each provided with offset lugs 35 arranged to pass behind extending shoulders 36 formed as part of the brackets 31. 90 This arrangement is simply to permit the motorman to leave either one of the rods down without retaining his foot on the pedal. It will be seen that if the rod be pushed down far enough the lug 35 will 95 catch on the shoulder and prevent the rod from returning. It can be released however by simply pushing the upper end of the rod sidewise.

The device is operated in the following 100 manner:—Assuming the car is approaching the switch as best shown in Fig. 2 of the drawing and that the motorman desires the car to take the switch, that is to pass on to the rails 13 and 14. All that he has to do 105 is to first turn the lever 22 to extend the bar until the hook 26 passes to a position almost directly above the slot indicated at "A" between the switch point and the track 14, then depress the right foot pedal to pass the hook 110 26 into the slot "A," and finally turn the lever to withdraw the bars. This will cause

the switch point to be pulled over and accordingly the car will pass onto the rails 13 and 14. Although both the bars 23 and 24 move when the rod 21 is turned still this 5 is not detrimental as only one of them is depressed at a time depending on whether the switch point is on the right or left hand side of the track:

What I claim as my invention is:—

- 10 1. In a switch point controlling device for cars the combination with the car, of a plurality of pivotally supported oppositely extending catch bars located beneath the front end of the car in advance of the car wheels, said bars being provided with hooked ends, means for varying the distance between the hooked ends of the bars and depressible means suspending the bars in a more or less horizontal position, as and for the purpose 20 specified.
2. In a switch point controlling device for cars the combination with the car, of a plurality of oppositely extending pivotally mounted catch bars located beneath the front 25 end of the car and in advance of the car wheels, said bars having their outer ends provided with hooks, means for withdrawing or extending the bars and depressible means suspending the outer ends of the bar 30 clear of the rails, as and for the purpose specified.
3. In a switch point controlling device for cars the combination with the car, of a pair of slidably mounted rack bars carried by 35 the car in advance of the front trucks, a pinion engaging with the rack bars, means operated from the car for rotating the pinion and thereby extending or withdrawing the rack bars, catch bars pivotally secured to the 40 outer ends of the rack bars, said catch bars having their outer ends provided with hooks, and depressible means normally supporting the catch bars clear of the track rails, as and for the purpose specified.
- 45 4. In a switch point controlling device for cars the combination with the car, of an open ended box suitably suspended beneath the car in advance of the front trucks, an upright shaft mounted centrally in the box 50 and passing upwardly into the car vestibule, means located in the vestibule for turning the shaft, a pinion fixed on the shaft and contained within the box, a pair of rack bars slidably mounted in the box and en- 55 gaging with the pinion, a pair of oppositely extending catch bars having the inner ends pivotally secured to the outer ends of the

rack bars and their outer ends provided with downwardly directed hooks, and depressible means normally suspending the outer ends 60 of the hooked bars clear of the track rails, as and for the purpose specified.

5. In a switch point controlling device for cars the combination with the car, of an open ended box suitably suspended beneath 65 the car in advance of the front trucks, an upright shaft mounted centrally in the box and passing upwardly into the car vestibule, means located in the vestibule for turning the shaft, a pinion fixed on the shaft and contained within the box a pair of rack bars slidably mounted in the box and engaging with the pinion, a pair of oppositely extending catch bars having the inner ends pivotally secured to the outer ends of the rack 75 bars and the outer ends provided with downwardly directed hooks, rods secured to the catch bars and passing upwardly through the car floor into the vestibule, said rods having their upper ends provided with foot 80 trips and spiral springs suspending the rods, as and for the purpose specified.

6. In a switch point controlling device for cars the combination with the car, of an open ended box suitably suspended beneath 85 the car in advance of the front trucks, an upright shaft mounted centrally in the box and passing upwardly into the car vestibule, means located in the vestibule for turning the shaft, a pinion fixed on the shaft and 90 contained within the box, a pair of rack bars slidably mounted in the box and engaging with the pinion, a pair of oppositely extending catch bars having the inner ends pivotally secured to the outer ends of the 95 rack bars and the outer ends provided with downwardly directed hooks, rods secured to the catch bars and passing upwardly through the car floor into the vestibule, said rods having their upper ends provided with 100 foot trips, brackets located on the car floor and receiving the rods slidably, spiral springs carried by the brackets and encircling the rods, cross pins carried by the rods and bearing on the upper ends of the 105 springs and means for locking the rods in the depressed position when depressed.

Signed at Winnipeg this 17th day of June 1912.

WALTER THORSTEINSON.
